APPARATUS FOR FORMING TERMINAL
ENDS OF COILS

John S. Stull, Chicago, Ill., assignor to Western
Electric Company, Incorporated, New York,
N. Y., a corporation of New York

Application December 22, 1944, Serial No. 569,371

9 Claims. (Cl. 140—103)

1

This invention relates to article forming apparatus and particularly to an apparatus for forming a terminal end of a coil.

The invention is particularly applicable to the forming of a terminal end of a vacuum tube heater coil. Such a coil may, for instance, comprise, as it comes from a coiling apparatus, a coil of .005" diameter tungsten alloy wire, the coil having an outside diameter of $\frac{1}{8}$ " and a length of $\frac{1}{4}$ "., each terminal end extending tangentially $\frac{1}{4}$ " from the coil at right angles to its longitudinal axis. In order to facilitate the mounting and connecting of the terminal ends of the coils into the vacuum tube structure and circuit, the tangent ends of each coil preferably should be preformed to required formations relative to the longitudinal axis of the coil. Due to the microscopic dimensions of the coils, great difficulty is encountered in handling, forming and giving the terminal ends a desired set and also providing a desired uniform formation to the ends of the coils.

An object of this invention is to provide a simple, efficient and practicable apparatus for uniformly forming and setting terminal ends of coils of the type above described.

In order to attain this object, in accordance with one embodiment of the invention as applied to the forming of one terminal end of the coil hereinbefore described, wherein the end is to extend parallel to and in coaxial alignment with the longitudinal axis of the coil, there is provided an apparatus comprising a pair of slidable jaws for clamping therebetween the coil on its outer periphery and at its inner periphery to an arbor carried by one of the jaws. A stationary terminal end positioning member cooperates with a bending edge on the arbor to first bend the tangent terminal end across the longitudinal axis of the coil during a unitary movement of the jaws, arbor and coil, the coil first being clamped during this movement, which is effected by the actuation of a hand lever operatively connected to one of the jaws. Following this a slidable and pivotal lever carrying a depending pin, which extends perpendicularly to the partially formed terminal end, is first advanced longitudinally therealong to laterally engage the same at a point adjacent the coil and then is advanced along an arcuate path to bend the terminal end laterally about a bending edge on the stationary member and into the path of an angularly formed face on a slidable bending shoe advancing in timed relation to the bending pin, the bending shoe then engaging, bending and setting the terminal end

2

against an angularly formed face on the stationary member so that when the coil is removed from the apparatus, the terminal end will be arranged parallel to and in coaxial alignment with the longitudinal axis of the coil. The slidable and pivotal lever and the slidable shoe are actuated to complete the forming and setting of the terminal end by a single continuous movement of a pivotal hand lever operatively connected thereto.

Other objects and advantages of the invention will be apparent from the following detailed description taken in conjunction with the accompanying drawings, in which

15 Fig. 1 is a fragmentary plan view, on an enlarged scale, of an article forming apparatus embodying the features of the invention, the parts thereof being shown in their normal positions;

20 Fig. 2 is a greatly enlarged fragmentary perspective view of a coil with a formed terminal end after removal from the apparatus;

Fig. 3 is a greatly enlarged fragmentary vertical cross section taken on the line 3—3 of Fig. 1;

25 Fig. 4 is a view similar to Fig. 1 showing an intermediate operative position of the apparatus in which the terminal end of the coil is partially formed;

Fig. 5 is a greatly enlarged fragmentary perspective view from below of a stationary coil and 30 terminal end supporting, positioning and terminal end forming element;

Fig. 6 is a vertical cross-section, partly in elevation, taken on the line 6—6 of Fig. 1;

35 Figs. 7, 8 and 9 are vertical cross-sections taken on the lines 7—7, 8—8 and 9—9 of Fig. 1;

Fig. 10 is a greatly enlarged fragmentary perspective view of one of the slidable coil clamping jaws;

Fig. 11 is a greatly enlarged fragmentary plan view showing the coil mounted on the arbor and 40 clamped thereto by the slidable clamping jaws;

Fig. 12 is a vertical cross section taken on the line 12—12 of Fig. 11;

Fig. 13 is a view similar to Fig. 11 showing the 45 terminal end of the coil partially formed and the bending pin in an advanced position;

Fig. 14 is a vertical cross-section taken on the line 14—14 of Fig. 13;

Fig. 15 is a view similar to Fig. 13 showing the 50 terminal end of the coil completely formed and set by the bending shoe; and

Fig. 16 is a vertical cross section taken on the line 16—16 of Fig. 15.

Referring now to the drawings, and particularly to Figs. 1, 6 and 9, the numerals 20 and 21

indicate spaced upper and lower irregularly shaped supporting plates, the lower plate being suitably attached by a block 22 and a bracket 23 (Fig. 6) to a work bench (not shown). At one side, the plates 20 and 21 are united in fixed spaced relation by a bar 24 and at the opposite side by a bar 27. Slidably mounted between opposed faces of the plates 20 and 21 are jaw members 28 and 29, which are guided rectilinearly at one side by the inner vertical longitudinal edge face of the spacer bar 24, the opposite side of the jaw member 28 being guided and retained by fixed plates or abutments 30 and 31. Fixed to the jaw member 29 is an arbor 34, which extends forward, as viewed in Fig. 1, between aligned arc-shaped cooperating jaw faces 35 and 36 formed on the jaw members 28 and 29, respectively. The jaw member 28 is normally urged toward the jaw member 29 by a leaf spring 37 secured at one end to the plate 21, with its free end engaging the left end of the jaw member (Fig. 6), the jaw member carrying a depending stop pin 38 arranged to engage the end face of the plate 21, thus limiting the inward movement of the jaw member (Figs. 1, 3 and 6). Journalled in the plates 20 and 21 is a pin 41 of irregular cross-section having an eccentric portion 42, which operates in a slot 43 in the jaw member 29, the pin having an actuator or operating handle 44 at its lower end (Fig. 9). Thus, when the handle 44 is rotated 180° in a counter-clockwise direction from its position shown in Fig. 1, where it engages a stop pin 45 and in which position the jaw member faces 35 and 36 are in their normal open position, to the position shown in Fig. 4, where the handle engages a stop pin 46, the jaw member 29 will be advanced toward the jaw member 28 to cause a coil 49 mounted on the arbor 34 to be peripherally clamped between the jaw member faces 35 and 36 and at its inner periphery to the arbor (Figs. 11 and 12). This movement of the jaw member 29 is such that, in addition to closing the jaw member faces 35 and 36 about the coil 49, a bodily movement of the jaw members 28 and 29, arbor 34 with the clamped coil occurs for a predetermined distance against the action of the spring 37 to the position shown in Figs. 4, 13 and 14 to partially form a terminal end 50 of the coil in a manner to be presently described.

Referring to Fig. 5, which illustrates, in perspective from below, the inner end of the fixed plate or abutment 31, which end is arranged adjacent the arbor 34, it will be noted that this plate is provided with a relatively thin stop fin 51 tapered towards its free end and extending toward the arbor 34. The bottom surface of the abutment 31 is relieved to provide a vertical face 52 arranged at a predetermined angle from and in the plane of the longitudinal axis of the arbor 34, and terminating at its inner end in a vertical bending edge 53, about which the partially formed terminal end 50 is bent and pressed against the vertical angular face 52 during the final bending thereof, by means to be presently described. At the juncture of the fin 51, with the vertical end face of the relieved portion of the abutment 31, there is formed a semi-cylindrical vertical groove 54. From its outer free end inwardly to a point clearing the rear face of the fin 51, the arbor is substantially semi-cylindrical in cross-section, as indicated at 51 (Fig. 3), with its upper face in the plane of the upper faces of the slidable jaw members 28 and 29. This form of the arbor 34 provides a bend-

ing edge 58 (Fig. 3) about which the terminal end 50 is bent in the partial forming thereof to the position shown in Figs. 13 and 14. The partial forming of the terminal end 50, by the means above described, is effected in the following manner: While the jaw members 28 and 29 are in their normal retracted positions with the jaw faces 35 and 36 open, as shown in Figs. 1 and 3, a coil 49 is threaded onto the arbor 34 until the tangent terminal end 50 to be formed abuts the stop fin 51, whereupon the coil is rotated counter-clockwise until the terminal end rests in the vertical groove 54, the coil and terminal end now assuming the position shown in Fig. 3. Thereafter, the jaw member faces 35 and 36 are closed upon the coil 49 by rotating the handle 44 counterclockwise 180° from the position shown in Fig. 1 to that of Fig. 4, whereby, in the manner previously described, the coil is first clamped to the arbor 34 and then the jaw members 28 and 29, with the clamped coil and arbor, are moved as a unit toward the left, as viewed in Figs. 11 and 12. During this latter movement, it will be obvious that the terminal end 50, which is engaged in the vertical groove 54 of the fixed plate or abutment 31, will be bent about the edge 58 of the advancing arbor 34 and abutted with the upper faces of the arbor and the jaw member 29 to the position shown in Figs. 13 and 14, wherein the terminal end extends across and in the plane of the longitudinal axis of the coil 49. Also, in the advance of the coil 49 with the arbor 34, the tapered end of the fin 51 will readily enter between the terminal end 50 and the first complete convolution of the coil 49 and separate the same, as shown clearly in Fig. 13, and provide a support for the terminal end during the bending operations.

To the right of the arbor 34, as viewed in Figs. 1, 4 and 6, is a mechanism for completing the forming and setting of the terminal end 50 partially formed by the means and in the manner previously described. This mechanism comprises an irregularly shaped pivotal and slidable lever 61 mounted on the upper supporting plate 20, the lever having a slot 62 at its left end (Fig. 1), through which extends a shouldered pin 63 riveted at its lower end (Fig. 6) to the plate 20 and its upper end having a thumb nut 64 screw-threaded thereonto, whereby the lever may freely slide on the plate and pivot about the pin and at the same time be maintained in close contact with the plate. At its right end, the lever 61 is provided with a V-shaped notch 65, in which is engaged, at all times, a pin 68 riveted to a slide plate 69 mounted between the supporting plates 20 and 21, the pin also extending through a slot 70 in the plate 20 and between the furcations of a bifurcated hand lever 71 disposed above the lever 61 and pivoted at 72 in a bracket 73 fixed to the plate 20. A leaf spring 74, having its free end bearing against the lever 61 and its opposite end held fixed in a notch 75 in the bracket 73, constantly acts to retain the V-shaped notch 65 of the lever in operative relation with the pin 68. The slide plate 69 is guided rectilinearly in its movements between vertical edge faces of the jaw member 29 and the bar 27. Depending from a plate 76 fixed to the left end of the lever 61 (Fig. 1) is a pin 77, the pin being of such length that it just clears the upper face of the jaw member 29. At its left end, as viewed in Figs. 1 and 6, the slide plate 69 is relieved to provide a bottom face 80, which is arranged to just clear the upper face of the jaw member 29 when the slide plate

is advanced to the position shown in Figs. 15 and 16. The relieved portion of the slide plate 69 is further reduced in thickness at its outer end to provide a lip 81 or bending shoe arranged in the plane of the terminal end 50 and having such a thickness that it may freely enter into the space between the upper face of the jaw 28 and the bottom face of the relieved portion of the fixed plate or abutment 31, as shown in Figs. 15 and 18, in the advanced position of the slide plate, the lip 81 being relieved or notched at its upper end, as viewed in Fig. 13, to permit it to pass under the fin 51. At its outer vertical end face, the lip 81 is formed at an angle, as indicated at 82, which is similar to the angle of the vertical face 52 of the fixed plate 31.

The manner of clamping the coil 49 and of partially forming the terminal end 50 thereof by a 180° actuation of the handle 44 having been previously described, the completion of the forming and setting of the terminal end by the last described means is effected in the following manner: As shown in Fig. 1, the hand lever 71 is in its normal position and, through its operative connection with the pin 68 fixed to the slide plate 69, the latter is in its fully retracted position with the pin abutting the right end face of the slot 70 in the fixed supporting plate 20. Also, by the engagement of the pin 68 in the notch 65 of the pivotal and slideable lever 61, the latter is in its fully retracted position with the left end face of the slot 62 thereof abutting the pin 63 carried by the fixed plate 20, the latter pin serving as a pivot about which the lever 61 rocks during its operative movement. In a single continuous clockwise movement of the hand lever 71 about its pivot 72, the terminal end 50 is bent about the vertical bending edge 53 of the fixed plate 31 and set against the vertical angular face 52 thereof to the position shown in Figs. 15 and 16. The first portion of this movement of the lever 71 to its position shown in Fig. 4 causes a rectilinear advance of the lever 61 and the slide plate 69 to the positions shown wherein the right end face of the slot 62 thereof is abutting the fixed pin 63, thus completing the rectilinear advance of the lever, the slide plate having been partially advanced. Figs. 13 and 14 illustrate, on a greatly enlarged scale, the relative positions of the lever 61 and slide plate 69 at this point in the movement of the hand lever 71. As shown in Fig. 13, the lever 61 is not illustrated, but the pin 71 carried thereby is shown in its advanced position and is laterally engaging the terminal end 50 adjacent the arbor 34. The continued clockwise movement of the hand lever 72 causes a counterclockwise movement of the lever 61 about its pivot 68, thereby advancing the pin 71 from its full line position to its dotted outline position and bending the terminal end 50 about the bending edge 53 of the fixed plate 31 to the dotted outline position (Fig. 13). In timed relation to this latter advance of the pin 71 to bend the terminal end to its latter position, the slide plate 69 has further advanced in behind the pin to laterally engage the terminal end and bend it sharply about the bending edge 53 while supported by the fin 51 and setting it against the vertical angular face 52 of the fixed plate or abutment 31, as shown in Figs. 15 and 16, the lip entering the space formed in relieving the abutment 31 to provide the angular face. The terminal end 50 is now completely formed and set and, upon removal from the apparatus, the terminal end will move from its set position into coaxial longitudinal

alignment with the longitudinal axis of the coil 49, as shown in full lines in Fig. 2. To remove the coil 49 from the apparatus, the hand lever 71 is first rocked counterclockwise to its normal position (Fig. 1) and thereafter the handle 44 is rocked clockwise 180° from its position shown in Fig. 4 to that of Fig. 1, whereupon the jaw member faces 35 and 36 are withdrawn from opposite peripheral portions of the coil and it is now free to be slid forward off the arbor 34 and another coil clamped in position.

What is claimed is:

1. An article bending apparatus comprising movable jaw members for gripping an article to be bent, an arbor element arranged between and movable with said members and having a bending edge about which a free portion of the article is bent in one direction, an abutment engaged by said article portion having a bending edge about which said article portion is bent in another direction, an actuator for moving one of said members to first cause the article to be gripped by said members and to thereafter cause a unitary movement thereof toward said abutment to bend said article portion in said one direction, and a movable bending pin for bending said article portion in said other direction.
2. An article bending apparatus comprising movable jaw members for gripping an article to be bent, an element having a bending edge extending perpendicular to the path of movement of and movable with said members for bending a free portion of the article in one direction, an abutment having a bending edge extending perpendicular to said first bending edge for bending said article portion in another direction, an actuator for moving one of said members to first cause the article to be gripped by said members and thereafter a unitary movement thereof toward said abutment to bend said article portion in said one direction, and a movable bending pin for bending said article portion in said other direction.
3. An article bending apparatus comprising movable jaw members for gripping an article to be bent, an element arranged between and movable with said members and having a bending edge about which a free portion of the article is bent in one direction, an abutment engaged by said article portion having a bending edge about which said article portion is bent in another direction and a surface extending from said bending edge against which said article portion is set in the bending thereof about said bending edge, said surface being formed at a greater angle than the desired angle to which said article portion is to be bent in said other direction, an actuator for moving one of said members to first cause the article to be gripped by said members and thereafter a unitary movement thereof toward said abutment to bend said article portion in said one direction, a movable bending pin for laterally engaging said article portion for partially bending the same in said other direction, and a movable bending shoe for further bending and setting said article portion against said surface of said abutment.
4. An apparatus for bending an uncoiled end of a coil comprising movable jaw members for clamping therebetween a coil adjacent the end to be bent, an arbor movable with said members engaging the inner periphery of the coil and having a bending edge extending parallel to the longitudinal axis of the coil about which said end is bent, an abutment for initially positioning said

end, said abutment cooperating with said bending edge to bend said end, and an actuator for moving one of said members to first cause the coil to be clamped by said members to said arbor and to thereafter cause a unitary movement thereof toward said abutment to bend said end.

5. An apparatus for bending an uncoiled tangent end of a coil comprising a pair of movable jaws for clamping therebetween a coil adjacent the end to be bent, an arbor arranged between and fixed to one of said jaws engaging the inner periphery of the coil and having a bending edge extending parallel to the longitudinal axis of the coil about which said end is bent in one direction across the longitudinal axis of the coil, an abutment engaged by and cooperating with said bending edge to bend said end in said one direction and having a bending edge extending perpendicular to the longitudinal axis of the coil about which said end is bent in another direction coinciding with the longitudinal axis of the coil, an actuator for moving said one jaw to first cause the coil to be clamped by said jaws to said arbor and thereafter a unitary movement thereof toward said abutment to bend said end in said one direction, and a movable bending pin for laterally engaging said end for bending the same in said other direction.

6. A bending apparatus for a coil comprising means for clamping a coil having a free tangential end in position, means for bending said tangential end to a substantially diametral position, means movable longitudinally of said coil for preliminarily bending said end at a point substantially on the longitudinal axis of the coil, and means movable substantially perpendicular to the axis of the coil to impart a final bend to the end.

7. A bending apparatus for a coil comprising an arbor for receiving a coil having a tangential end, one end of said arbor being cut away to form a substantially semi-cylindrical section, means for bending said end substantially diametrically across said sectional end of said arbor, means movable longitudinally of said coil for preliminarily bending a portion of said diametrically ex-

tending end to a position substantially longitudinal of the coil, and means movable substantially perpendicular to the axis of said coil for imparting a final bend to said portion.

8. A bending apparatus for a coil comprising an arbor for receiving a coil having a tangential end, one end of said arbor being cut away to form a substantially semi-cylindrical section, means for clamping a coil to said arbor, means for bending said end substantially diametrically across said sectional end of said arbor, means movable longitudinally of said coil for preliminarily bending a portion of said diametrically extending end to a position substantially longitudinal of the coil, and means movable substantially perpendicular to the axis of said coil for imparting a final bend to said portion.

9. A bending apparatus for a coil comprising an arbor for receiving a coil having a tangential end, one end of said arbor being cut away to form a substantially semi-cylindrical section, means for separating an end convolution from the coil, means for bending said end substantially diametrically across said sectional end of said arbor, means movable longitudinally of said coil for preliminarily bending a portion of said diametrically extending end to a position substantially longitudinal of the coil, and means movable substantially perpendicular to the axis of said coil for imparting a final bend to said portion.
